UNITED STATES PATENT OFFICE

150,107

DESIGN FOR A BAG FRAME OR SIMILAR ARTICLE

Benjamin Blacher, Providence, R. I., assignor to Blacher Brothers, Inc., a corporation of Rhode Island

Application February 11, 1948, Serial No. 144,399

Term of patent 3½ years

(Cl. D87—2)

To all whom it may concern:

Be it known that I, Benjamin Blacher, a citizen of the United States of America, residing at Providence, county of Providence, State of Rhode Island, have invented a new, original, and ornamental Design for a Bag Frame or Similar Article, of which the following is a specification, reference being had to the accompanying drawing forming a part thereof.

Fig. 1 is an elevation of a bag frame showing my new design;

Fig. 2 is a top plan view of the showing in Fig. 1; and

Fig. 3 is an edge view of the showing in Fig. 1.

The essential parts of the design are shown in full lines.

I claim:

The ornamental design for a bag frame or similar article, substantially as shown and described.

BENJAMIN BLACHER.
